MILTON W. CLARK, OF WORCESTER, MASSACHUSETTS, ASSIGNOR TO R. BALL & CO.

Letters Patent No. 100,118, dated February 22, 1870.

IMPROVED BLIND-SLAT.

The Schedule referred to in these Letters Patent and making part of the same.

To all whom it may concern:

Be it known that I, MILTON W. CLARK, of the city and county of Worcester, and State of Massachusetts, have made a new and useful Improvement in Revolving Blind-Slats; and I do hereby declare that the following is a full, clear, and exact description of the construction of the same, reference being had to the annexed drawings making a part of this specification, in which—

Figure I is a side view of the slat, and

Figure II is an end view of the same.

The same letters in each figure denote the same parts.

My improvement consists in making the shoulder a of the tenon a with an offset, c , cut down within a proper distance of the tenon a , so that only a small part, c , of the end of the slat A will rub upon the stile of the blind when the slat revolves. By this means there is not only less friction between the blind-slat and the stile, but another objectionable feature is removed, for in painting the blinds the paint is apt to gather between the stile and the ends of ordinary slats, thus binding the latter and rendering it impossible to open or close them without great difficulty; indeed in the effort to move them the wire by which they are connected is oftentimes broken and otherwise injured.

In conclusion I would remark that I am aware that the ends of the blind-slats have heretofore been rounded off for the purpose of preventing them from binding against the stile. Slats made in such form have their tenons cut by a hollow angle or cutter, which forms the tenons and bevels off the ends of the slat. But this operation is attended with many disadvantages, for the wood of which the slat is formed is apt to be split or broken off by the anger; and the slat when completed is a different article from that which is the subject of my application, for it has no offset at all,

and its rounded or beveled ends not only detract from the appearance of the blind, but leave a considerable space between them and the blind-slat. My improved slat has none of these defects. The ends are not beveled or rounded or cut away, but a small offset is cut in the shoulder of each tenon, which, while it allows the ends of the blind to be straight, as heretofore, keeps them from binding against the stile, and prevents the paint which gathers on the ends from impeding the working of the slats. The formation of this offset has not been practicable heretofore, and it is only since the employment of my improved blind-slat cutter, for which Letters Patent of the United States have been recently granted me, that a slat formed as herein shown has been made.

The cutter is arranged and constructed, as will be seen by reference to the patent referred to, so as to cut both the square offset and the tenon at one operation, and to prevent the slivering of the wood, which has constituted one of the drawbacks to the use of other cutters.

The formation of the square offset and the prevention of the splitting of the wood have not been effected before; and it is these two points, more especially the first, that distinguish from all others the slat which constitutes the subject of my present patent.

That which I claim as my invention, and desire to secure by Letters Patent, is—

As a new article of manufacture, a revolving blind-slat, provided with a square offset, c , formed in the shoulder of each tenon a , in the manner and for the purposes herein shown and set forth.

MILTON W. CLARK.
